(57) **CLAIM**

The ornamental design for a mounting seat for hanging a wrench socket, as shown and described.

DESCRIPTION

FIG. 1 is a perspective view of a mounting seat for hanging a wrench socket, showing my new design;

FIG. 2 is a front view thereof;

FIG. 3 is a rear view thereof;

FIG. 4 is a left side view thereof;

FIG. 5 is a right side view thereof; and,

FIG. 6 is a bottom view thereof.

The broken lines depict environmental subject matter, are for illustration only and form no part of the claimed design. The top view forms no part of the claimed design and is omitted.
